(57) **CLAIM**

We claim the ornamental design for a financial transaction machine, as shown and described.

DESCRIPTION

FIG. 1 is a front, perspective view of a financial transaction machine showing our new design.

FIG. 2 is a front elevational view of FIG. 1.

FIG. 3 is a back elevational view of FIG. 1.

FIG. 4 is a side elevational view of FIG. 1.

FIG. 5 is an opposite side elevational view of FIG. 1.

FIG. 6 is a top plan view of FIG. 1; and,

FIG. 7 is a bottom plan view of FIG. 1.

The broken lines in the drawings illustrate environmental structure on the article and form no part of the claimed design.
